ABRASIVE TOOL

Merlyn G. Williams, Jr., Downers Grove, and
Arthur Dahl, Chicago, Ill.

Application October 11, 1946, Serial No. 702,636

2 Claims. (Cl. 51—187)

1

This invention relates to abrasive tools, and has to do with an abrasive tool of the type wherein a strip or sheet of abrasive cloth or paper is removably secured to a pad or holder designed to fit in the hand of a user.

It is an object of the present invention to provide a device of this character which will make it possible to remove and replace the abrasive material with a minimum amount of effort.

It is also an object of the present invention to provide an abrasive tool of the character described incorporating features of design and construction which will assure simple assembly and operation as well as production in volume quantities at a relatively low unit cost.

It is a further object to provide a tool of this kind which will accommodate fastening of a wide range of thicknesses of abrasive cloth or paper.

Another object resides in the provision of an improved tool of the character described comprising an elongated pad having a bottom face and transverse end faces across which the abrasive material may be stretched and held taut by means of a clamping member mounted for movement about an upright central spindle presenting end surfaces in cooperation with the upper surfaces of the pad between which ends of the abrasive material may be tightly pressed.

With these and other objects in view, the invention consists in certain novel features of construction and combination of parts, the essential elements of which are set forth in the appended claims, and a preferred form of embodiment of which is hereinafter shown with reference to the drawing which accompanies and forms a part of this specification.

In the drawing:

Fig. 1 is a top perspective view of the present abrasive tool, illustrating the hand of a user in position for manipulating and operating the same.

Fig. 2 is a side elevational view of the tool.

Fig. 3 is a vertical sectional view taken on line 3—3 of Fig. 2.

Fig. 4 is a top plan view thereof showing the clamping member rotated to a position preliminary to being turned into a position to clamp the abrasive material, said latter position being indicated in dotted lines.

Referring now in detail to the drawing, 10 indicates the flat lower surface of a pad or block of rectangular plan, formed of wood or other suitable material. Reference numeral 11 indicates a flat upper surface substantially parallel

2

to the lower surface 10. The end faces 12 in transverse relation to the side faces 13 slant or curve inwardly and upwardly to form a smooth juncture with the upper face 11. Slots or recesses 14 formed in the pad to slant inwardly and downwardly from the upper surface 11 of the pad, extending the full width thereof and terminating short of the bottom surface 10, form upwardly opening pockets across the surface of the pad marking the juncture of the surface 11 and the end faces 12. The slots 14 accordingly provide pockets in which the opposite ends 15 of a sheet or pile of abrasive paper or cloth 16 may be inserted at such time as the portion of the paper intermediate said ends is wrapped about the face 10 and the end faces 12 of the pad.

Cooperating with the pad to exert a downward clamping pressure against the portion of the paper 16 slightly inward from the ends 15 thereof 20 disposed in the slots 14 is a clamping member or block of elongated rectangular plan, formed of material similar to that of the pad, such as wood or the like. The clamping member is preferably of such size and shape as to present longitudinal side walls or surfaces 18 at such a distance apart that the fingers of a user's hand may be comfortably and securely gripped thereabout as shown in Fig. 1. The transverse ends 19 are also preferably located a distance inward from the opposite end faces 12 of the pad when the clamping member is in operative position as shown in Fig. 2 (and in dotted lines in Fig. 4) so as to expose a maximum amount of surface of the abrasive material 16 facing upwardly from the pad. 25 Accordingly the lower face of the clamping member overhangs or overlaps the entrance to the slots 14 only a distance compatible with insuring engagement with the portion of the abrasive material immediately outside the slots.

40 A spindle in the form of a screw 20 having a head 21 extending through openings pierced centrally upwardly through the pad and clamping member, provides an axis about which the clamping member may be swung in a horizontal path 45 toward and away from an operative position as shown in Fig. 4. The surface of the clamping member surrounding the threaded portion of the screw 20 projecting upwardly therefrom is preferably counterbored as at 22 to dispose a wing nut 23 having threaded engagement with the screw 20 in depressed relation to the upper surface of the clamping member. The pad is similarly counterbored at the lower limits of the opening formed therein for the screw 20 so as to 50 position the head 21 of the screw in non-protrud-

ing relation to the lower face of the pad. Accordingly, the screw 20 and wing nut 23 cooperate with the pad and clamping member to grip the abrasive material just outside the entrance to the slots 14, and at the same time permits the clamping member to be easily turned horizontally from a position of engagement with the abrasive material to a position clear thereof so as to clear the slots 14 when it is desired to remove the abrasive material and substitute a new strip or sheet.

As will be observed in Fig. 2, the lower face of the clamping member is preferably concaved inwardly so as to avoid contact between the entire area of the facing surfaces of the pad and clamping member extending between the portions thereof which engage the abrasive material. Thus the wing nut 23 may be turned through a substantial range to vary the pressure exerted by the cooperating surfaces of the pad and clamping member against the abrasive material without hindrance of contact between the central portions of the cooperating or facing surfaces of the pad and clamping member.

The sides 18 of the clamping member are preferably grooved or recessed longitudinally as at 25 to provide surfaces with which the fingers of a user's hand may be positively retained against slipping in the direction of the article being operated upon by the abrasive material, during use of the present tool.

The upper face of the clamping member is also preferably bevelled at each end as at 26 to shorten the height of the transverse end surfaces thereof and thereby locate the upper corner of the ends 19 of the clamping member in a plane tangent to the curve formed by the abrasive material at the ends of the pad at a distance substantially above the lower corners of the pad.

While the form of mechanism herein shown and described is admirably adapted to fulfill the object primarily stated, it is to be understood that it is not intended to confine the invention to the embodiment herein shown and described, as it is susceptible of embodiment in various forms, all coming within the scope of the claims which follow.

What is claimed is:

1. An abrasive tool comprising a pad of rectangular plan having a flat bottom face, transverse end faces rising upwardly therefrom, and a top face substantially parallel to said bottom face, transverse slots intersecting the top face in proximity to said transverse end faces, said slots slanting inwardly and downwardly from said upper face of the pad, a strip of abrasive encir-

cling said bottom face and transverse end faces and having its end portions disposed in said slots, and means adapted to exert downward pressure on portions of said abrasive strip immediately outside said slots to hold said strip taut including a clamping member having a bottom face overlapping said portions of the abrasive strip immediately outside said slots, and a central upright spindle connecting said pad and clamping member about which said pad may be horizontally turned toward and away from a position in engagement with said abrasive strip.

2. An abrasive tool comprising a pad of rectangular plan having a flat bottom face, transverse end faces rising upwardly therefrom, and a top face substantially parallel to said bottom face, transverse slots intersecting the top face in proximity to said transverse end faces, a strip of abrasive encircling said bottom face and transverse end faces and having its end portions disposed in said slots, and means adapted to exert downward pressure on portions of said abrasive strip immediately outside said slots to hold said strip taut including a clamping member having a bottom face overlapping said portions of the abrasive strip immediately outside said slots, said bottom face of the clamping member being concave throughout the area thereof intermediate portions engaged with the abrasive strip, and a central upright spindle connecting said pad and clamping member about which said pad may be horizontally turned toward and away from a position in engagement with said abrasive strip.
